UNITED STATES PATENT OFFICE.

WILLIAM BRUCE KNAPP, OF STONEHAM, MASSACHUSETTS.

SHOCK-ABSORBER.

949,654.

Specification of Letters Patent. Patented Feb. 15, 1910.

Application filed June 10, 1909. Serial No. 501,317.

To all whom it may concern:

Be it known that I, WILLIAM BRUCE KNAPP, of Stoneham, county of Middlesex, State of Massachusetts, have invented an improvement in Shock-Absorbers, of which the following is a specification.

This invention relates to shock-absorbers for automobiles and the like, of the type comprising a cylinder and piston, connected one with the axle and the other with the frame of the vehicle, and having means for establishing open communication between the opposite end-portions of the cylinder, permitting movements of the piston and cylinder toward and from each other, and said piston bearing check-valves permitting unrestrained movements of the piston and cylinder in a direction toward each other.

The invention has for its object to provide means whereby movements of the piston and cylinder in a direction toward each other are severely restrained during the last part of a long stroke yet unrestrained during the first part of such stroke, as well as during short strokes.

Figure 1 is a longitudinal vertical section of a shock-absorber, embodying this invention. Fig. 2 is a plan view of the closing-plate which is arranged in the cylinder and adapted to be engaged by the downwardly moving piston. Fig. 3 is a modified form of closing-plate.

As here shown, *a* represents a hollow cylinder having closed ends or heads *a'*, *a''*, and adapted to be filled with a non-congealable oil or equivalent material, and *b* represents a piston contained in said cylinder and attached to a piston-rod *b'*, which extends through a suitable stuffing-box *b''*. The cylinder *a*, as here shown, has a by-pass *c*, extending along its side from end to end or thereabout, for establishing open communication between the opposite end portions thereof, at opposite sides of the piston. The piston *b*, has one or more holes *b³* through it, and valves *b⁴* are provided for said holes, which may be of any suitable construction, adapted to operate as check-valves, opening when the piston is moving in one direction and closing when the piston is moving in the opposite direction. Said cylinder and piston are adapted to be connected respectively with the axle and frame of the vehicle by any suitable means. It is herein designed to close the hole or holes *b³* in the piston when said piston has moved in a di-

rection toward the cylinder for a suitable distance, so that further movement of the piston in the same direction will be severely restrained, although not checked. To accomplish this result a closing-plate *g* is employed, which is made as a flat ring of suitable diameter to be contained in the cylinder, and said plate is arranged beneath the piston and in the downward path of movement thereof, so as to be engaged by it. Said plate is particularly constructed to close the holes *b³* when engaged by the piston, yet as a modified form of my invention said plate may have small holes through it, see Fig. 3, so that instead of wholly closing said holes *b³* it will partially close them. Hence the closing-plate herein referred to may act either to wholly or partially close said holes. Said plate is secured to or has a collar *g'* arranged at the center thereof, which is free to slide on a supporting and guiding-rod *g²*, arranged vertically in the cylinder, and said plate is held yieldingly in a predetermined position by means of a lifting-spring *g³*, which encircles said rod *g²* and bears at one end against the lower end of the cylinder and at the opposite end against the plate or collar thereof. The rod *g²*, as here shown, has adjustably connected with it a limiting-stop for limiting the upward movement of the closing-plate, and said stop consists of two collars *g⁴*, *g⁵*, arranged on the screw-threaded end of said rod *g²*. The piston-rod is made tubular for a suitable portion of its length to receive said collars *g⁴*, *g⁵*. The spring *g³* acts to lift the closing-plate and hold it with its collar *g'* in engagement with the end of the lowermost collar *g⁴*. Said limiting-stop may be adjusted by turning the collars on the screw-threaded end portion of the rod *g²*.

As the piston and cylinder move in a direction toward each other their movements will be unrestrained by the opening of the valves, until the piston engages the closing-plate, and its further movement is severely restrained by said plate closing the hole or holes *b³*, although such further movement is not checked for the reason that the by-pass *c* is in open communication with the cylinder at both ends. Hence during short movements of the piston and cylinder toward each other they are unrestrained, but during a long movement the first part thereof is unrestrained and the last part severely restrained. As the piston and cylinder move

- in a direction away from each other their movements are restrained owing to the check-valves closing, although such movement is permitted by the by-pass.
5. Having thus described my invention, what I claim as new and desire to secure by Letters Patent is:—
1. A shock-absorber comprising a cylinder and a piston contained therein having 10 holes through it and having valves, and a movable closing-plate arranged in said cylinder, in the downward path of movement of the piston, for closing one or more of the holes therein, whereby further downward 15 movement of the piston is restrained, substantially as described.
  2. A shock-absorber comprising a cylinder and a piston contained therein having holes through it and having valves, and a yield- 20 ingly supported closing-plate arranged in said cylinder, in the downward path of movement of the piston, for closing one or more of the holes therein, whereby further downward movement of the piston is re- 25 strained, substantially as described.
  3. A shock-absorber comprising a cylinder and a piston contained therein having holes through it and having valves, and a sliding closing-plate arranged in said cylin- 30 der, in the downward path of movement of the piston, for closing one or more of the holes therein, whereby further downward movement of the piston is restrained, sub- stantially as described.
  35. 4. A shock-absorber comprising a cylinder and a piston contained therein having holes through it and having valves, and a movable closing-plate arranged in said cylinder, in the downward path of movement 40 of the piston, for closing one or more of the holes therein, whereby further downward movement of the piston is restrained, and an adjustable stop for limiting the upward movement of said closing-plate, substan- 45 tially as described.
  5. A shock-absorber comprising a cylinder and a piston contained therein having holes through it and having valves, and a movable closing-plate arranged in said cylinder, in the downward path of movement 50 of the piston, for closing one or more of the holes therein, whereby further downward movement of the piston is restrained, and a guide-rod upon which said closing-plate slides and a lifting-spring for said closing-plate, substantially as described.
  6. A shock-absorber comprising a cylinder and a piston contained therein having holes through it and having valves, and a movable closing-plate arranged in said cylinder, in the downward path of movement of the piston, for closing one or more of the holes therein, whereby further downward movement of the piston is restrained, a 60 guide-rod for said closing-plate having a screw-threaded end-portion and two collars arranged on said screw-threaded end-portion, which form an adjustable limiting-stop for the closing-plate, substantially as de- 65 scribed.
  7. In a shock-absorber, a cylinder having a longitudinal by-pass, a piston contained in said cylinder having valve-openings, valves for said openings, a movable closing-plate arranged in said cylinder, in the downward 70 path of movement of the piston, adapted to be engaged and moved downward by said piston, and which, when in engagement with the piston, closes the valve-openings therein, whereby further downward movement of 75 the piston is restrained, substantially as de- scribed.

In testimony whereof, I have signed my name to this specification, in the presence of two subscribing witnesses.

WILLIAM BRUCE KNAPP.
